2 SHEETS—SHEET 2.

UNITED STATES PATENT OFFICE.

HOWARD S. IRVINE, OF TRENTON, NEW JERSEY.

SURFACE-CLEANING MACHINE.

1,095,327.

Specification of Letters Patent.

Patented May 5, 1914.

Application filed November 7, 1912. Serial No. 730,045.

To all whom it may concern:

Be it known that I, HOWARD S. IRVINE, a citizen of the United States, residing at Trenton, in the county of Mercer and State of New Jersey, have invented new and useful Improvements in Surface-Cleaning Machines, of which the following is a specification.

My present invention relates to surface cleaning machines whereby the surface dirt is agitated by suitable brush means, and collected by the generation and conducting of air currents through dirt retaining means pervious to air.

The principal objects of my invention are to provide a machine of the character described which is simple in construction, and hence, inexpensive to manufacture; a machine having capacity for cleaning a surface 20 of considerable width, as it is moved thereover; and, one capable of operation and adjustment so as to perform its function in an efficient manner.

Other objects of my invention will appear in the following detailed description, taken in connection with the accompanying drawings forming a part of this specification, and in which drawings

Figure 1 is a longitudinal sectional view through a machine constructed according to my invention. Fig. 2 is a top plan view of the same. Fig. 3 is an elevation of an adjustable wheel fork. Fig. 4 is a sectional view of co-acting nuts used in connection with the fork disclosed in Fig. 3. Fig. 5 is a fragmentary elevation of means for attaching the dust collectors to the air ducts. Fig. 6 is a sectional view disclosing clutch mechanism. Fig. 7, is an end view of the brush hood, showing means for attaching it to the frame, and gearing to operate the brush.

Similar characters refer to similar parts throughout the several views.

A suitable vehicle is provided preferably comprising a frame 8, supported by wheels 12 and caster-wheel 17. The frame 8 may be built up and comprise longitudinally extending members 9 coming together at the forward end of the vehicle, to form a tongue 10; and, transverse members 11 rigidly spacing members 9. The wheels 12 are carried by an axle 13 rotatable in bearings 14 on frame members 9. The wheel 17 is disposed at the forward end of the vehicle frame 10, and is adjustable vertically with respect thereto, for a purpose to be subsequently set

forth. This wheel is preferably mounted in a forked member 16, having a screw threaded stem 18 passing through frame 8 at tongue 10. This stem carries a nut 19, having a depending annular flange 20, to fit into the aperture in frame 8, and a nut 21 below the nut 19, and abutting against said flange, but not binding against said frame. By this means, the wheel may follow in the path of movement imparted to frame 8.

The device comprises a frame 8, on one end of which are supported on the shelf portions 28, of one of the transverse members 11, dust collectors 25, and from the other end is suspended by means of links 29, a brush hood 23. Intermediate the dust collectors 25 and the brush hood 23, is a substantially circular fan-casing 24 connected on one side to the upper side of the brush hood 23 by a plurality of spaced-apart conduits 26, and connected on its opposite side to the dust collectors 25, by a pair of conduits 27.

Chamber 24 receives a fan 30 adapted, upon rotation, to draw air through hood 23 and ducts 26, and forward the same through ducts 27 and dust collectors 25. Each of the dust collectors preferably comprises a rigid outer casing 31 having an opening 32, for egress of air, remote from the communication of the duct 27 therewith, a bag 33, within casing 31, and over opening 32 therein, this bag being pervious to air, but adapted to retain the solid matter conveyed from hood 23. As convenient means for facilitating removal of solid matter from the casings 31, I provide a flange 34 adjacent the end of each casing 31 and having upwardly extending screw threaded stems 35. On each duct 27 I provide a flange 36, having openings 37 to receive said stems, so that when thumb nuts 38 are screwed upon said stems, the casing 31 is held rigidly with duct 27 to compel the air to find egress through opening 32.

As preferred means for actuating fan 30 by movement of the wheels 12, I provide motion transmitting means designated generally by 29. Each wheel 12 carries with it, upon rotation, a gear 40, co-meshing with pinion 41, each pinion rotating a shaft 42, which shafts are axially aligned and carried by bearings 43 on frame 8. These shafts, through clutches 44, impart movement to a shaft 45. When the vehicle moves forward, however, such clutches are adapted to permit rearward movement of the vehicle with-

out the shafts 42 imparting movement to shaft 45. The fan shaft is designated by 46, and suitable gearing, comprising co-meshing gears 47 and 48, the former being rigid with shaft 46 and the latter rigid with a shaft 49; and co-meshing bevel gears 50 and 51, the former carried by shaft 49 and the latter by shaft 45, imparts movement from said latter shaft to the fan shaft, in order to create air currents as previously described. Each clutch 44 preferably comprises a ratchet-wheel 52 rigid with shaft 45, and a ratchet 53 co-acting therewith, carried by shaft 42 as through flanged wheel 54. Thus, as the wheels 12 rotate in a forward direction, movement is imparted to shaft 45 successively through gears 40, pinions 41, shafts 42, wheels 54, ratchets 53 and ratchet-wheels 52. However, if the vehicle moves rearwardly, the ratchet 53 does not engage with the teeth of wheel 52, so as to impart movement to shaft 45 and the fan 30 is rendered inactive.

Within hood 23 I provide an agitator 55 for the surface dirt, which comprises a drum-like brush 56, mounted on a shaft 57. This shaft extends through vertically disposed elongated apertures 58 in the end walls of hood 23, and has a sprocket 59 at each end. The shaft 57 is rigidly and adjustably supported by depending brackets 60 having slots 61 to receive the stems of bolts 62, carried by frame 8. Thus by raising or lowering frames 60, the brush 56 may be adjusted relative to hood 23, so as to successively perform its function to agitate particles of dirt within said hood.

As means for imparting movement to shaft 57, I provide a sprocket-wheel 63 on each shaft 42 adapted to drive a second sprocket-wheel 64, revolvably mounted on the frame 8, above sprocket-wheel 59, through chain 65. Revolvable with each sprocket-wheel 64 is a second sprocket-wheel 66, which drives a chain 67 drawn about said sprocket-wheel 59. Thus, regardless as to whether the vehicle moves forwardly or rearwardly, the brush 56 is revolved. It is obvious from this arrangement that I have provided an efficient means for imparting movement to the brush 56 which agitates the dirt when revolved and causes the dirt to be forwarded to the ducts by means of the fan.

The operation of the machine is as follows: Assuming that the vehicle is forwarded over the surface to be cleaned, as the

wheels rotate movement is simultaneously imparted to brush 56 and fan 30. The brush 56 breaks up or agitates the particles of dirt on the surface, and within the hood 23. The fan 30, through rotation, causes suction in ducts 26 drawing the particles of dirt from hood 23 and forwarding the same through ducts 27 to dust collectors 25. The relative proximity of hood 23 and brush 56 to the surface upon which the machine acts, may be adjusted by axial movement of fork 16, relatively to frame 8 or the brush may be adjusted relatively to such surface, by raising or lowering brackets 60.

Changes in details may be made without departing from the spirit or scope of my invention; but,

I claim:

1. A surface cleaning machine comprising a vehicle frame, a suction device mounted thereon, including a brush hood, a fan casing, a fan, a dirt collector, said hood, casing and collector being rigidly connected, a brush rotatably mounted in said hood, means for operating said brush, means for adjusting said brush independently of said hood, and means for adjusting said frame and simultaneously adjusting said hood.

2. In a surface cleaning machine, the combination with a vehicle frame, a brush hood depending therefrom, and a tongue extending from said frame, of a forked member, a wheel rotatably carried in the lower end thereof, a threaded stem formed upon the upper end of said member, a nut threaded upon said stem, said stem passing through said tongue, another nut threaded on said stem, a depending flange formed upon said second mentioned nut, and said flange bearing against the first mentioned nut.

3. In a surface cleaning machine, the combination with a vehicle frame, of a brush hood suspended from said frame, said hood having its ends provided with vertical slots, a brush rotatably mounted therein, a shaft for said brush passing through said vertical slots, depending brackets for supporting said brush, said depending brackets being provided with longitudinal slots in their upper ends and a set screw engaged in said slot and said vehicle frame.

HOWARD S. IRVINE.
